REPEATING FUSE

Herbert L. Rawlins, Wilkinsburg and Andrew H. Bakken, Edgewood, Pa., assignors to Westinghouse Electric & Manufacturing Company, East Pittsburgh, Pa., a corporation of Pennsylvania

Application November 29, 1935, Serial No. 52,098

11 Claims. (Cl. 200—126)

This invention relates to multiple unit circuit interrupters and specifically to circuit interrupters of the type in which a fuse tube is released and falls to a conspicuous position when the fuse is blown. In one form of the circuit interrupter to which this invention particularly appertains, a plurality of expulsion fuse units are used, the blowing of the first fuse causing the second to be connected in the circuit and so on. The invention herein described is particularly related to the mechanism for establishing the connection through the second fuse when the first is blown. The mechanism by which the fuse is released when the fuse is blown is the subject of the patent to Herbert L. Rawlins, Patent No. 2,183,083, issued December 12, 1939, and assigned to the assignee of this application.

When a conventional fuse is blown on a power line, an attendant must replace it. In power lines through rural districts, it is desirable that the attendant be not required to visit the fuse locations often. Hence, it is the practice on such lines to provide a plurality of fuses, preferably of the expulsion type due to the large arc extinguishing capacity of those devices, which can serve in succession. If the first is blown during a lightning storm some of the others may be blown during the same storm, but it is unlikely that all of them will be blown, and hence, some of the fuses will continue to serve until time for the next regular visit of the attendant.

It is an object of the invention to provide a mechanism for such automatic transfer of the connections to a new fuse tube.

It is an object of this invention to locate such mechanism for establishing the new connections at the top of the fuse tube. The tube being open only at the bottom, the mechanism is thus protected from the fumes expelled by the tube.

It is a further object of this invention to provide an interrupter of this type which shall include a suitable housing for the actuating mechanism therefor, in order to protect that mechanism from the weather and from accidental or malicious interference with its operation.

It is a further object of this invention to provide a mechanism which is inherently capable of producing a sufficient delay during the reclosing operation to permit the fault to clear itself or the disturbance caused by lightning to cease and which, at the same time, includes means whereby the final movement of the transfer mechanism shall be quick enough to insure well established contact.

It is a further object of this invention to pro-

vide a simple means for resetting the transfer mechanism when the fuse tube is reset.

It is a further object of this invention to provide the needed delay in the transfer mechanism and yet to limit the interruption of service to a short interval, say one second.

Other objects of the invention will be apparent from the following description and the accompanying drawings, in which—

Figure 1 is a side elevation partly in section of the multiple fuse device.

Fig. 2 is a front elevation of the same.

Fig. 3 is an enlarged vertical section through the mechanism associated with the top of any one fuse tube, and

Fig. 4 is a similar section showing the mechanism in the position which it assumes after the fuse tube is blown.

The device is mounted in any convenient way. As illustrated, it is mounted upon a cross arm 1 on a pole of the power line. A support from the cross arm holds an insulator 2. At its upper end the insulator has a supporting device 3 which holds a connecting bar 4 of copper. A similar supporting device 5 at the bottom of the insulator holds a bar 6, also of copper.

The mechanism at the bottom of each fuse tube includes a dog 10 and a cooperating spring 11 which are described in greater detail in the above mentioned copending application. The tube 12, of which there are three shown, contains a fusible element which is connected by a conductor shown at 13 to a fastening upon the dog 10. The spring 11 acts to exert an upward thrust upon the tube 12 and so seats the cap 15 within a recess in the member 20. The cap 15 closes the upper end of the tube 12.

A housing 22 is provided above the upper end of each tube 12. Preferably the housings are made of molded insulating material. The lower walls of the housings are relatively thin but the upper parts are thickened, the change in thickness being indicated at 23 and 24. The additional thickness at 24 provides two opposed ledges each of which is useful for receiving a bolt by which the housing is secured to the copper strip 4. A notch in the shoulder 23 provides a seat for the pivot 25 of the member 20.

The member 20 consists of two side plates each having its pivot 25 which seats in the notch in the shoulder 23 of the housing. The pivots extend outward from the outer sides of the side plates. Between the side plates, there are cross connections, one of which is the pin 26, another is the bar 27, and still another the bar 28. The

principal cross connection is the floor 29 which constitutes the bottom of the member 20. It has a recess 30 which receives the cap 15 of the tube 12.

The portion of the member 20 which in Fig. 3 extends toward the bar 4 has a deep notch in each side plate, providing projections, of which the upper ones 31 support the pin 26 between them. The other side of the notch affords flanges 33 which serve to stiffen the floor 29. The left-hand portion of the notch 30 is shown as somewhat oblique but it may, if desired, be made more nearly parallel to the side of the cap 15. It affords an abutment by which the cap 15 may position the member 20.

The portion of the bottom of the member 20 on the other side of the notch is provided upon the upper face with an eye 35 into which a spring 36 is secured. The other end of the spring 36 is fastened into a stirrup 37 which is secured in place by a binding post 39, extending to the outside of housing 22. The stirrup 37 has two arms, each with an eye. One eye receives the spring 36 and the other receives a spring 40.

A flexible copper conductor 41, secured by binding post 39 between the two arms of the stirrup 37, connects the binding post 39 to the cross bar 28 of the member 20, and thus the fuse 12 is connected into the circuit through the cap 15 and the member 20. The cross bar 28 not only affords a convenient place to secure the connector 41 but also strengthens the member 20. It is located at the bottom of a notch in each side member separating the pivot 25 and that portion of the floor which carries the eye 35. The notches in the side members reduce their mass, the moment of inertia of the member 20 being thus kept as small as can conveniently be accomplished.

A cylindrical dashpot receptor 43 is molded into the upper portion of the housing 22. The receptor is lined with a brass sleeve 44 to afford good sliding surface for the dashpot piston 46. The sleeve may be omitted if desired. Although the fit is improved by means of the sleeve, there is sufficient leakage around the piston 46, which is preferably formed of molded graphite or other suitable material, to permit the dashpot to move slowly.

A link 50 connects the dashpot piston 46 with the lower end of the spring 40. This link is curved to the right (Fig. 3) at its lower end in order to position that end at the right of the pin 26. This end of the link 50 receives the lower end of the spring 40. The cross pin 26 in the position shown in Fig. 3 is seated in the notch 51 in the link 50.

The left-hand fuse (Fig. 2) is normally the first to operate, and the conducting portions of the housing 22 associated therewith are connected to the cross bar 4 by a strap connector 53. A binding post 54 affixed to the housing 22 associated with the first fuse is connected, by means of a copper link 56, with the binding post 39 of the next housing, and a similar link 56 connects the binding post 54 of the second housing to the binding post 39 of the next housing and so on. The last housing has no binding post 54.

The ends of binding posts 54 inside the housings are equipped with contact blades 55 adapted to engage the end 58 of the floor of the member 20. This end 58 is shaped to slidably enter between the contact blades and they are resilient enough to afford good contact pressure.

The normal circuit through the device before any of the fuses have blown is through the first fuse only, or more specifically, from the terminal strip 4, through the strap conductor 53, binding post 39, conductor 41, pivoted member 20, cap 15, the fuse link in tube 12 having the end portion 13, and dog 10 to terminal strip 6. The other two fuses are not connected in the circuit since the binding post 39 of their respective housings is connected by one of the conductors 56 only to one of the contacts 55 which contacts are not electrically connected to the terminal strip 4 until after the associated fuse has blown and the cooperating pivoted member 20 makes contact therewith.

In the operation of the device, when the current in the line exceeds a predetermined magnitude, either because of lightning or from an overload, short circuit or other cause, the fusible element within the fuse tube 12 associated with the first housing is blown. As the link within this tube melts, the gases and fused metal are expelled downward. They cannot escape upward because the cap 15 closes the tube at the top.

Before the fuse link is melted, it holds the conductor 13 from movement and this, as explained in the above-mentioned copending application, holds the dog 10 against rotation. Because of the restraint upon the dog 10, the spring 11 acts to press the tube 12 and the cap 15 upward. The pressure of cap 15 against the member 20 tends to produce clockwise rotation of that member (Fig. 3) about the pivot 25, thus resisting any tendency the spring 36 may have to move the member 20 counter-clockwise and also holding the dashpot piston 46 in its uppermost position by the pressure of pin 26 in notch 51.

The conductor 13 being released by the fusion of the link, releases the dog 10 and permits the spring 11 to rotate the dog relative to the tube 12 upon which it is supported. As a result, the fuse moves downward so as to disengage the recess 30 in the member 20. As soon as the fuse disengages the member 20, the spring 36 rotates that member 20 counter-clockwise about the pivot 25. The force exerted by the spring 36 in effecting this rotation is opposed by the dashpot piston 46. This opposition continues and restricts the movement of the member 20 to a speed fixed by the amount of leakage in the dashpot until the cross bar 27 contacts with the link 50 and moves it toward the left in Fig. 3 sufficiently to release the cross pin 26 from the notch 51. By this time, the line of action of the spring 36 has been moved well to the right of the pivot 25 and the effect of the spring is correspondingly increased. Thus when the release of the dashpot piston occurs, the spring 36 rotates the member 20 rapidly in a counter-clockwise direction to bring the terminal 58 into contact with the blades 55.

During all of this movement, the projections 31 on the two side plates restrain the link 50 from erratic movements. During the first part of the movement similar guidance is given by the flanges 33. Thus, the link 50, although pivoted at one end and held at the other by a long flexible spring, is prevented from getting out of place.

The connection from the binding post 39 of the left-hand housing is now through the flexible copper member 41 and the cross bar 28 to the floor of the member 20 and so to terminal 58 and the blades 55 of the corresponding binding post 54, thence it is along the link 56 to the binding

post 39 of the central housing. The circuit is thus established through the second fuse, the first fuse having swung to its normal open circuit position. When the second fuse is blown, the circuit is transferred in a similar way to the third fuse. Any number of fuses may be provided, but for ordinary conditions, three would be sufficient to assure continuity of service under ordinary operating conditions.

When the attendant visits the apparatus and discovers that a tube 12 is in open-circuit position, he may remove the blown unit, replace the blown fuse, and return the tube 12 to its vertical position, all by means of a suitable hook stick, the hook portion thereof being inserted in the ring 60. When a fuse is being swung from the open to the closed circuit position, it first contacts the left-hand side of the notch 30 which extends below the housing, as seen in Fig. 4. Movement of the fuse is thereby communicated to the member 20 and that member is rotated clockwise from the position shown in Fig. 4 to the position shown in Fig. 3 during the final stages of the movement of the fuse.

The spring 40 returns the dashpot piston 46 automatically to the illustrated position as soon as the pin 26 releases the link 50 during an opening operation.

During the fuse replacement operation, the clockwise movement of the member 20 causes the pin 26 to contact the edge of the link 50 and to move that link slightly to the left (Fig. 3), until the pin 26 enters the notch 51. The movement of the link 50 toward the left is opposed by the spring 40 and when the pin 26 has arrived at the notch 51, the spring 40 causes the link to again move to the right, engaging the pin in the notch 51, thus returning all of the parts to the position illustrated in Fig. 3. The apparatus is then restored to its normal operative condition and is ready to repeat the above described sequence of operation.

The spring 11, exerting pressure through tube 12 and cap 15, acts to hold the parts in the normal operative position. Hence the device is automatically resettable. Further, since each of the switching members 20 automatically moves into engagement with the cooperating contact 55 as soon as the associated fuse operates or is manually swung to the open circuit position, the structure automatically adjusts the electrical circuits through itself to assure proper sequential operation regardless of the position of the several fuse units.

The action of the device after the first fuse 12 has blown should normally occupy about a second. This is ample time for a fault to clear and for the gas to escape from the tube 12. The time interval may, however, be readily adjusted to any desired value by means such as the valve 70. Regardless of the time interval, the final portion of the movement of the member 20 is so rapid that arcing is avoided at the contacts 55; this is an important feature of the invention and adds much to its reliability of operation.

Many variations in the structure will occur to those skilled in the art and we do not wish to be limited by the specific structure disclosed.

We claim as our invention:

1. In a circuit opening device, a plurality of expulsion fuses of the tube type, means for pivotally supporting each of said fuses at the lower end thereof, said means including a spring which exerts an upward thrust upon the fuse tube, and mechanism adjacent the upper ends of the tubes

for operatively associating the fuses with the circuit in succession as each fuse is blown in turn.

2. In a circuit opening device, a plurality of fuses of the tube type, each pivotally supported at the lower end thereof, a separate mechanism adjacent the upper end of each of the tubes for operatively associating the fuses with the circuit in succession as each fuse is blown in turn, and a separate insulating housing for enclosing the mechanism adjacent each tube.

3. In a multiple-unit circuit interrupter, a connector for each unit for connecting another unit into the circuit upon operation of the first unit to open-circuit condition, spring operated means for moving the connector into position for so connecting the second unit, mechanism for delaying the action of said spring operated means, means carried by the spring operated means for disconnecting it from the delaying mechanism upon movement of the spring operated means beyond a predetermined point, and a spring for returning the delaying mechanism to its original position upon said disconnection, said spring establishing reengagement upon return of the connector moving means to its original position.

4. In a circuit opening device, a plurality of fuse tubes, each containing a fusible element and each open at one end only, a separate housing disposed adjacent the closed end of each of said tubes, a mechanism in each housing, which includes a recessed member pivotally supported for movement between two positions, the closed end of the respective tube being receivable in said recess of said pivoted member, a spring, the line of action of which lies to one side of the pivot point of said member for biasing that member toward one of said two positions, said tube normally holding said member in the other of said two positions against the force exerted by said biasing spring means associated with each tube for moving it upon fusion of the element therein and thereby releasing the associated recessed member, and permitting said biasing spring to move said member to said other position, a connector moved by the recessed member, and conductors cooperating therewith when said member has been moved to said other position to connect a different fuse tube into the circuit.

5. In a circuit interrupter, a plurality of expulsion fuses, means for pivotally supporting each of said fuses at the lower end thereof, said support means including biasing means for exerting an upward thrust upon each fuse, and mechanism adjacent the upper ends of the fuses for operatively associating the fuses with the circuit in succession as each fuse is blown in turn.

6. A circuit interrupter comprising a plurality of drop-out fuse units, each unit comprising a fuse tube having a fusible element therein, a movable contact member, means biasing said tube into engagement with said contact member and to an open circuit position, said fusible element normally restraining said fuse tube from movement to the open circuit position, a fixed contact in circuit with an adjacent fuse unit, and means for moving said movable contact member into engagement with said fixed contact upon the movement of said tube to the open circuit position, following the fusion of said element for connecting an adjacent fuse element in the circuit.

7. In a circuit interrupter, a pair of terminal members insulatingly mounted with respect to each other in parallel vertical spaced relation, a plurality of fuse members pivotally supported

from the lower terminal member, a corresponding plurality of housings of insulating material mounted on the upper terminal member, a contact member in each of said housings normally adapted to releasably engage a fuse member, a connection from said upper terminal member to the contact member of the first housing for normally establishing a circuit through the first fuse member to the lower terminal member, and means including a mechanism within each housing associated with the contact members for operatively connecting the fuse members in succession in circuit with said terminal members as each fuse member is blown in turn.

8. In a circuit interrupter, a plurality of expulsion fuses, means for pivotally supporting each of said fuses at the lower end thereof to enable the fuse to swing to open and closed positions, a pivoted switch member adjacent the upper end of each of said fuses, each of said switch members having a recess in which the upper end of a respective fuse is seated for normally holding said fuses against rotation about their pivotal supports, means responsive to the operation of a fuse for disengaging its upper end from the recess in its corresponding switch member, means for moving said switch members about their pivots in response to the operation of its respective fuse, and means engageable by a switch member upon movement thereof for establishing a circuit connection to an adjacent fuse.

9. In a circuit interrupter, a fuse comprising a tube, a fusible element therein and means for moving said tube upon fusion of said element, a switch member normally in circuit with said fusible element, said switch member having a notch in which one end of said tube is seated for holding said tube in the closed position, means for moving said switch member upon fusion of said element and motion of said tube, means for retarding the initial movement of said switch member, the final movement of said switch mem-

ber being completed with a snap action, and means engageable by said switch member upon the completion of its movement for establishing a new connection to the circuit.

- 5 10. In a circuit interrupter, a fuse tube pivotally mounted at one end for swinging movement about its pivot to open and closed positions, a contact member movable between two positions and normally held in one of said positions by said 10 fuse tube for delivering current thereto, said contact member holding said fuse tube against rotation about its pivot when said contact member is in said normal position, means associated with said fuse tube which is operable when the fuse 15 is blown to cause said fuse tube to release said contact member, means operable upon the release of said contact member to move said member to the other of said positions, and a contact 20 cooperating with said member when it has been moved to said other position for establishing a new circuit through the interrupter around the blown fuse.
- 25 11. In a circuit interrupter, a fuse tube pivotally mounted at one end for swinging movement about its pivot to open and closed positions, a contact member movable between two positions and having a recess therein, said fuse tube being seated in said recess when in the closed position for holding said contact member in one of said 30 positions and for holding said fuse tube against movement about its pivot, means responsive to the disengagement of said fuse tube from said recess for moving said contact member to the other of said positions, means for retarding the initial 35 movement of said contact member, the final movement of said contact member being completed with a snap action, and means engageable by said contact member upon the completion of its movement for establishing a new connection to the circuit.
